PRESSURE RELIEVING JOINT FOR
BUILDING CONSTRUCTION

Peter Masterson, Chicago, Ill.

Application October 3, 1934, Serial No. 746,697

2 Claims. (Cl. 72—106)

This invention relates to improvements in compressible fillers heretofore employed to avoid the effects of excessive compression stresses in the exterior facing material of buildings such as stone or terra cotta, which stresses frequently cause cracking or defacing of such material. Sometimes, for example, terra cotta tiles forming the exterior surfaces of buildings, and often having only moderate crushing strength, are so stressed by crushing forces later set up in the main structure of the building, that corners or whole faces of tiles are cracked or wholly broken away, and the exterior surface be thus permanently damaged.

These results have been avoided to a large degree by the use of compressible fillers inserted between adjacent layers of stone or tile at suitable intervals, as broadly disclosed in Patent No. 1,552,392 issued on September 1, 1925, to John

P. Cowing. The present invention is directed more particularly to an improvement in the form of compressible fillers disclosed in said patent so as to include in their construction a novel mastic sealing material, whereby a more permanent weatherproof, watertight joint may be provided in a simple, inexpensive and efficient manner.

The invention may best be understood by reference to the accompanying drawing, in which

Fig. 1 is a vertical transverse section of a portion of building wall to which the device of my invention is applied.

Fig. 2 is a perspective view, drawn on a much larger scale than Fig. 1, showing a portion of a filler piece constructed in accordance with my invention as it may be applied to a building wall.

Fig. 3 is a view similar to Fig. 2 showing a modified form of filler piece.

Fig. 4 is an enlarged detail section illustrating one method of original application of a filler piece of the type shown in Fig. 2 between two blocks such as shown in the structure illustrated in Fig. 1.

Fig. 5 is a view similar to Fig. 4, but showing the manner in which the superimposed stresses have caused distortion or flattening of the filler piece, but maintaining a weatherproof joint between said blocks.

The illustrative structure shown in Fig. 1 comprises a main wall 5 of concrete or other material and an outer facing 6 made up of blocks 7, 7 such as terra cotta tile. As usual, tie bolts 8 and 9 are anchored in the main wall at vertical intervals, and carry shelf angles 10, 11 each presenting a horizontal ledge which supports each superimposed tier of tiles.

The several layers of tile may be secured to

gether, as usual, by mortar indicated at 15, excepting that at certain intervals, and preferably at least once between each adjacent pair of shelf angles, a row of compressible filter strips 20, 20 is interposed in end-to-end relation between abutting tiers of tile blocks, in the usual arrangement. These filler pieces may, for instance, be disposed directly above a shelf angle, as shown at the top of Fig. 1, or they may be interposed between intermediate tiers of tile, as shown near the bottom of Fig. 1. Moreover, mortar may or may not be used as desired in connection with the joint formed by the filler strips. In the form shown in Fig. 1, mortar is applied in the usual manner so as to fill the adjacent rebates or recesses 21 formed between the inner and outer surfaces of the tiles 7, but Figs. 4 and 5 show a joint in which the mortar has been omitted.

One of the principal difficulties encountered in the use of compressible filler pieces such as previously used for the purpose described, is that of insuring a weatherproof joint between the blocks and the filler strips, due to unevenness in the adjacent faces of the blocks, or the uneven compression or expansion that often occurs in various areas or zones of the exterior shell, thereby producing unequal compression of the fillers. This may tend to open up the joints at certain points so as to permit water to seep through the shell, and it may also cause the fillers, or portions of them, to become displaced, either inwardly or outwardly, so as to destroy their effectiveness and, in extreme cases, detracting from the appearance of the building.

In carrying out my invention, I provide an improved form of filler designed to combine the compressible features heretofore utilized in such devices, with means serving to provide a permanent weatherproof seal for the joint, and compensating for changes in shape thereof, while in use. As herein illustrated, said filler piece consists of an elongated strip 20 formed by upper and lower cover layers 23, 24 preferably of non-corrosive metal such as copper or lead, said layers being formed of a single sheet folded along the inner edge and vertically spaced from each other, as shown. A compressible element 25 is interposed between these layers, said element being arranged to withstand normal crushing stresses, but constructed to be flattened under excessive vertical pressure. In the form shown in Fig. 2, said element consists of a sheet of metal such as copper or lead, corrugated and arranged with its flutes extending lengthwise of the strip. The outer edge of the compressible

element 25 is normally disposed at a distance from the free outer margins 23^a and 24^a of the cover layers 23 and 24, respectively, so as to leave a marginal space or recess between the open margins of said layers. Within this space is introduced a quantity of mastic, in the form of a continuous strip 26, extending the full length of the filler piece. The mastic is preferably of a permanently plastic type of waterproof material such as has heretofore been employed for waterproof joints and filling material in many ways, but which, due to its relative plasticity, is not generally practicable for use alone as a substitute for metallic compression joints of the type disclosed herein.

In carrying out the present invention, mastic is applied to the open edge of my improved form of filler piece so as to produce a novel article of manufacture, in which the mastic is permanently incorporated as a part of the filler piece before it is applied to the building structure.

The mastic is preferably secured to the adjacent metal surfaces of the filler piece by adhesion, and is normally arranged substantially flush with the margins of the layers 23 and 24.

In the modified form of my improved filler piece shown in Fig. 3, the compressible element 25^a interposed between the cover layers 23 and 24 consists of a strip of corrugated metal arranged with its flutes extending transversely of the filler strip. A strip of mastic 26^a closes the outer or open margins of the cover layers 23 and 24 as before, and extends into engagement with the adjacent fluted margin of the compressible element 25^a.

The use and advantages of my improved form of filler piece will now be more clearly manifest to those skilled in the art. The arrangement is such that the filler strip may be applied in the usual manner between adjacent surfaces of superimposed building blocks as shown in Fig. 4, with its outer edges preferably spaced a slight distance from the outer surfaces of the adjacent blocks 7, 7. Under normal loads the filler strip will only be flattened a sufficient amount to extrude a small amount of mastic from between the open edge of the filler piece as shown, which will be sufficient to completely close the space between the blocks, and form a waterproof joint as clearly indicated in Fig. 4. In the event of excessive vertical pressures, the filler piece will be compressed to a greater or less degree so as to compensate for such pressures, but in all cases the mastic portion 26 will be maintained in direct contact with the adjacent surfaces of the

blocks 7, 7 so as to retain an effective seal for the joint, as indicated in Fig. 5.

Among the further advantages of my invention is the arrangement whereby the mastic is applied to the filler piece during the process of manufacture of the latter so as to produce a building element that can be conveniently shipped and handled as a finished unit. This is of especial advantage due to the difficulties usually encountered when mastic is applied directly to masonry joints during construction, where the presence of dust, dirt, cement and the like usually render it almost impossible to insure a tight waterproof seal. With my improved article of manufacture the mastic is applied during the manufacture of the filler piece so as to insure uniformly successful results. The mastic can be applied far more conveniently under suitable heat and pressure, and far more care can be afforded in providing clean metallic surfaces to which the mastic is applied, preferably by adhesion, as described.

Although I have illustrated and described certain embodiments of my invention, it will be understood that I do not wish to be limited to the exact construction shown and described, but that various changes and modifications may be made without departing from the spirit and scope of my invention as defined in the appended claims.

1. A compressible filler for use as a pressure relieving joint in a wall structure, comprising flat upper and lower metal layers, and intervening compressible means arranged to sustain a predetermined weight without substantial compression but to be compressed by excessive pressure, said compressible means terminating at a distance from a lateral margin of said metal layers to form a recess, and mastic mounted within said recess arranged to be partially extruded therefrom when said compressible means is compressed.

2. A compressible filler for use as a pressure relieving joint in a wall structure, comprising flat upper and lower metal layers and intervening compressible means, an undulating metal layer arranged to sustain a predetermined weight without substantial compression but to be compressed by excessive pressure, said undulating layer terminating a substantial distance from a lateral margin of said metal layers to form a recess, and mastic permanently mounted within said recess, arranged to be partially extruded therefrom when said undulating layer is compressed.

PETER MASTERSON.
